UNITED STATES PATENT OFFICE.

WALTER E. MOWREY, OF ARNOLD, NEBRASKA.

PHOTOGRAPHIC-PRINTING MACHINE.

1,304,796.

Specification of Letters Patent. Patented May 27, 1919.

Application filed July 19, 1918. Serial No. 245,687.

To all whom it may concern:

Be it known that I, WALTER E. MOWREY, a citizen of the United States, residing at Arnold, in the county of Custer and State of Nebraska, have invented certain new and useful Improvements in Photographic-Printing Machines, of which the following is a specification.

The invention provides a photographic apparatus which admits of printing, retouching, and enlarging of photographs, the appliance obviating the usual dark room and the covering of the head when retouching, thereby simplifying the various operations and adding materially to the comfort of the operator.

The invention has for its object to provide an appliance embodying a cabinet which is adapted to be positioned to admit light and which is provided with door controlled openings whereby the light may be utilized as required according to the nature of the work to be performed.

The invention provides an appliance specially adapted to be applied to a window so as to control the admission of light, the appliance embodying a light cabinet and a light screen, the latter being provided with openings which are adapted to be normally closed by slides which may be moved to regulate the admission of light, the openings of the screen being covered by material of such color as to modify the actinic properties of the light admitted into the room.

The drawing illustrates a preferred embodiment of the invention, however, it is to be understood that in adapting the same to meet different conditions, various changes in the form, proportion, and minor details of construction may be resorted to without departing from the nature of the invention as claimed hereinafter.

In the drawings:

Figure 1 is a front view of a photographic appliance embodying the invention, the light cabinet being in section,

Fig. 2 is a vertical transverse section on the line 2—2 of Fig. 1, looking to the left as indicated by the arrows, showing the appliance fitted to a window,

Fig. 3 is a horizontal section on the line 3—3 of Fig. 1,

Fig. 4 is a horizontal section on the line 4—4 of Fig. 1, looking upward as indicated by the arrows, and

Fig. 5 is a detail view of the removable section whereby the opening in the top of the light cabinet may be varied.

Corresponding and like parts are referred to in the following description and indicated in the several views of the drawing by like reference characters.

The appliance embodies a light cabinet and a light screen and the same being of such proportions so that when fitted to a window the latter is completely covered thereby excluding the light from the room excepting such as is admitted through properly controlled openings. The light cabinet is closed at its top, bottom, front, and ends, and is open in the rear so as to admit light into the cabinet through the window when the device is in position. The cabinet is mounted upon suitable legs 1. The bottom 2 of the cabinet is extended in the rear so as to overlap the sill 3 of the window as indicated most clearly in Fig. 2. The ends 4 of the cabinet are comprised between the front 5 and top 6, and the bottom 2 of the cabinet. The front 5 is provided with an opening which is covered by means of a door 7, the latter being fitted closely so as to exclude rays of light from escaping from the cabinet into the room. The top 6 has an opening 8 formed therein and this opening is adapted to be varied in size so as to receive different size frames. A section 9 is removably fitted in the opening 8 so as to vary the size thereof and this section is of L-form whereby to vary the size of the opening 8 in two directions. It is to be understood that any number of sections 9 may be provided and the same may be of any form and size to admit of adapting the opening 8 to the article to be supported therein. The edges of the opening 8 are rabbeted so as to provide supporting ledges 10 for receiving a printing frame or other article to be supported in the opening. The removable section 9 has its inner and outer edges rabbeted

to conform to the edges of the opening 8 whereby the section may be supported when in position and in turn support a frame or other article to be retained in the opening 8. 5 The top 6 may be extended to provide a table or support for receiving sundry articles to be conveniently at hand.

The opening 8 is controlled by means of doors 11 the same being hinged to the underside of the top 6 so as to swing downward. The doors 11 are spring actuated and reconnected to the top 6 by means of spring hinges 12 of any type. For controlling the doors 11 a treadle 13 is provided as this 15 treadle is connected by means of cords 14 with the respective doors. Guide pulleys 15 give proper direction to the cords 15. The doors 11 are of such construction as to obtain a close fit against the under side of the top 6 so as to prevent the escape of any rays 20 of light through the opening 8 when the doors 11 are closed. The cords 14 pass through openings formed in the bottom 2, such openings being of a size to prevent the 25 escape of light and to insure a close fit therein of the cords 14. The light screen is indicated at 16 and consists of a panel and like part of a size to completely close the upper portion of the window. This screen is located in the rear of the light cabinet and extends upwardly from the rear edge of the top 6. When the appliance is fitted to a window the rear portion of the bottom 2 overlaps the sill 3 of the window 17 and the 30 rear side of the cabinet comes opposite the lower portion of the window thereby freely admitting light into the cabinet. The screen 16 covers the upper portion of the window 17 and is fitted thereto in a manner to exclude rays of light. One or more openings 40 18 are formed in the lower portion of the screen and are closed by means of slides 19 which are mounted in suitable guide-ways formed on the screen at the sides of the 45 openings 18. The openings 18 are covered by material 20 of a color to modify the actinic properties of light so that the light admitted into the room through the openings 18 will not affect the sensitized films or 50 plates thereby admitting of negatives being held in substantially the same manner as in a dark room. When the slides 19 are moved so as to cover the openings 18 all light is excluded from the room and by 55 opening the slides 19 more or less any required amount may be admitted into the room so that the work may be properly conducted.

From the foregoing it will be understood 60 that the appliance when in position for service is fitted to the window of a room or like place, the light from the outside having unobstructed passage into the light cabinet through the opening back or rear thereof.

For printing the frame containing the negative is placed in the opening 8 after which 65 the treadle 13 is depressed thereby exposing the negative to the light within the cabinet whereby the printing is effected. For retouching the negative is supported in the opening 8 in any desired way and the treadle 13 is depressed and may be held lowered in 70 any manner. The retouching may be affected in the usual manner. For enlarging the negative may be fitted to the opening 75 closed by the door 7 and the camera may be properly adjusted according to the degree of enlargement. It is to be understood that if required a reflector may be placed on the outside of the window so as to control and 80 direct more light into the cabinet. In case the light is too strong it is to be understood that the window may be suitably covered by means of a sheet, either of textile or 85 paper.

The foregoing description and the drawings have reference to what may be considered the preferred, or approved, form of my invention. It is to be understood that I 90 may make such changes in construction and arrangement and combination of parts, materials, dimensions, et cetera, as may prove expedient and fall within the scope of the appended claims.

Having thus fully described my invention, 95 what I claim as new and desire to secure by Letters Patent is:—

1. A photographic printing apparatus, comprising a cabinet to be fitted to the lower portion of a window opening and having a 100 light receiving opening in the rear and a negative receiving opening in the top, and a screen supported by the cabinet and adapted to cover the upper portion of the window opening and having a light opening therein 105 and a closure for said light opening.

2. A photographic printing apparatus to be applied to a window opening, the same comprising a cabinet having a light receiving opening in its rear and a negative receiving opening in its top, a screen projected vertically from the cabinet in line with the rear side thereof and formed with a light opening, a closure for the light opening in the screen and means for closing the negative receiving opening of the cabinet. 115

3. A photographic printing apparatus, comprising a cabinet having a light receiving opening in one of its vertical sides and having a negative receiving opening in its 120 top, a supporting frame work for the cabinet, a door disposed within the cabinet and adapted to close the negative receiving opening and a treadle mounted upon the supporting frame work of the cabinet and having connection with the door for closing the negative receiving opening.

4. Photographic printing apparatus, com-

prising a cabinet having its rear side open and provided in its top with a negative receiving opening, and having a door controlled inspection opening in its front, a door for closing the negative receiving opening, a treadle connected with the door for closing the negative receiving opening and mounted upon the frame work supporting the cabinet, a screen mounted upon the rear

portion of the cabinet and having a light 10 opening therein and closing means for said light opening.

In testimony whereof I affix my signature in presence of two witnesses.

WALTER E. MOWREY.
